GAS OR VAPOR PUMP

Anne J. M. A. van der Does de Bije, The Hague,
NetherlandsApplication August 13, 1932, Serial No. 628,732,
and in the Netherlands October 28, 1931

1 Claim. (Cl. 230—143)

Pumps are already known comprising intermeshing screws which are enclosed by a casing in such a manner that together and with the casing they form compartments adapted, on rotation of 5 the screws, to move from the suction side towards the pressure side. In such arrangements various means are employed to ensure that the flanks of the screw threads shall make a close fit.

The invention relates to another arrangement 10 for ensuring that the screws shall be satisfactorily sealed with respect to one another and to the casing. Moreover, the invention can be employed in order to obtain progressive compression in the compartments. This allows the 15 pump to operate in an economical manner as a gas pump, since the said compression can be made to be approximately isothermal.

According to the invention, the pump is provided with a passage which extends from the 20 pressure chamber of the pump to a closed compartment formed by the screws and the casing. The word "passage" must be taken to include a number of passages working in parallel, or a branched passage which opens into several consecutive compartments. The expression "a compartment" in this connection therefore does not mean "one compartment".

The pump is prepared for operation by the 25 pressure chamber being filled with so much liquid that the liquid under the action of the gas pressure flows through the passage to the compartments. Preferably, passages are arranged in the bodies of the screws and provided with branch passages, the openings of which lie in the bottoms of the spaces between the screw threads. The liquid entering the compartments flows over 30 the flanks of the screw thread and also to the outer circumference, so that a liquid seal, which is continually being renewed, is formed both between the screw threads, and between each 35 thread and the casing. The screws therefore need not contact with one another or with the casing.

If the passages are made to open in various 40 points longitudinally of the screws, and if the 45 openings are properly dimensioned, the result can be obtained that during the movement of a compartment from the suction side towards the pressure side the volume of the mass of gas trapped in the compartment decreases owing to a greater amount of liquid being admitted than escapes by leakage. In these circumstances the gas is compressed during its movement towards the pressure side, and this compression may be 50 approximately isothermal owing to cooling of

the injected liquid, and/or to transference of heat to a cooling jacket of the casing.

The suction chamber can readily be formed to collect the liquid, so that leaking liquid is trapped in the compartments with the gas or vapour and continuously returned to the pressure chamber. 60

In a pump according to the invention which is to be used as an air pump for a steam engine, the condensed water may be used as the liquid that is forced to the compartments. In 65 an air compressor the sealing liquid may, for example, be oil.

In the accompanying drawing two embodiments of the invention are illustrated by way of example. 70

In Fig. 1 (vertical section) and Fig. 2 (horizontal section), the casing 1 is provided with inlet branches 2, 3 and an outlet branch 4. Since this pump is intended to be an air pump for a condensation plant, the driving shaft 5 extends through a stuffing box of the outlet branch 4. The gear wheel 6 drives the pinions 7 and 8 of the screw shaft 9, 10. 75

The screws 11, 12, 13, 14 are secured to the 80 shafts 9, 10 and their pitch is less than their diameter. The screw 11 is left handed and the screw 13 right handed. The threads of these two screws fit as closely as possible together and against the casing 1. The second pair 12, 14 is a duplicate of the pair 11, 13. It is clear that 85 here the use of two pairs of screws has the object of balancing the axial forces.

Bored in the bodies of the screws are passages 90 15 and a number of branch passages 16, the openings of which lie in the bottoms of the gaps between the threads. The branches 16 are spaced so far from the suction chamber 17, 18 that they are connected with closed compartments only.

If the pressure chamber 19 is filled with liquid 95 to the level 20, the liquid will be forced into the passages 15 by the gas pressure and in the manner described above the screw threads are sealed with respect to one another and to the casing.

If, on account of leakages, such a large amount 100 of liquid flows into the suction chambers 17, 18 as to reach the level 21, any further liquid entering is taken up by the compartments and automatically returned to the pressure chamber.

If it is not desired for the ends of the screws 105 in the pressure chamber to be partly or wholly immersed in the liquid, the casing may be provided with a system of passages somewhat as shown in Fig. 3. The passage 22 opens at the bottom of the pressure chamber 19. The liquid forced therein flows through branches 23 into the 110

compartments between the screw threads. The passages 22 may have a branch 24, whereby liquid can be forced to points at a higher level and adjacent to the screws. If necessary, the liquid from these branch passages may be sprayed against the bodies of the screws. The level 25 of the liquid in the pressure chamber may consequently be kept low, so that the gas forced into the pressure chamber from the compartments does not have to bubble through the liquid. The passages 22 may be combined to form a cooling jacket, and cooling tubes may be arranged in the liquid space of the pressure chamber.

If the openings 16, 23 are properly dimensioned, it is possible as stated above, to supply to the compartments a progressive amount of liquid in addition to the amount necessary for sealing, so that during the forward movement of the trapped mass of gas the desired compression is obtained.

It has already been stated that the first branch passage 16 on the suction side opens into a closed compartment. In certain circumstances however, for example with a screw having only few convolutions, it may be useful to inject the liquid before the compartment is entirely closed. In that case the degree of filling will be somewhat reduced.

What I claim is:—

In a gas or vapor pump, single threaded intermeshing screws having a pitch smaller than the diameter of the screws, a casing enclosing said screws, a compartment formed by said screws and said casing, a pressure chamber in said casing, and a passage arranged in the body of at least one of said screws, said passage opening into said compression chamber and into the gap between the threads of said screw immediately adjacent the front pressure face of the thread.
